FRED WAITE, OF OTLEY, ENGLAND.

PLATEN PRINTING-MACHINE.

SPECIFICATION forming part of Letters Patent No. 727,502, dated May 5, 1903.

Application filed August 26, 1899. Serial No. 728,583. (No model.)

To all whom it may concern:

Be it known that I, FRED WAITE, a subject of the Queen of England, residing at The Lindens, Otley, England, have invented certain new and useful Improvements in Platen Printing-Machines, of which the following is a specification.

This invention particularly relates to improvements in that type of platen printing-presses in which the sheet is carried from the feed-table by grippers on the platen into position to be printed upon; and it consists in an arrangement for avoiding the necessity of moving the platen for this purpose, also in a modified form or arrangement of grippers.

In the accompanying drawings, Figure 1 is a side elevation of such parts of the machine as are necessary to illustrate the application of the mechanism for stopping the impression and for double inking. Fig. 2 is a similar view to Fig. 1 of certain of the parts, but moved to an operative position. Fig. 3 is a plan view of certain of the parts shown in Fig. 1. Fig. 4 is a view of the opposite side of Fig. 3 to that shown in Fig. 1. Fig. 5 is a sectional view illustrating a modified form of gripper and method of working it. Fig. 6 is a plan view of the platen and gripper. Fig. 7 is a sectional view showing the method of working the grippers independent of the platen. In this figure the grippers are shown in the position they occupy when they have laid hold of the sheet projecting from the edge of the feed-table. Fig. 8 is a similar view with the grippers in the position they occupy after carrying the sheet onto the platen. Fig. 9 is a plan view of the grippers in the position shown in Fig. 7.

The type-bed D is of ordinary design and is carried by arms 2 on each side, swinging upon the rocking shaft 3. The arms 2 are oscillated by rods D² on each side, connected to the cranks or eccentric studs D³ in the wheels D⁴, fixed on each end of the shaft B³. The ends 4 of the rods D² are coupled to eccentric projections 5 on the shaft 6, mounted in the bearings 7 in the arms 2. A tappet-arm 10 is fixed on the shaft 6, and when this arm engages the antifriction-roller 12 the shaft 6 is rotated in its bearings to bring the eccentric ends 5 sufficiently around toward the platen to prevent the impression being

made. In order that this may take place when it is desired to stop the impression either momentarily or automatically at every other stroke when double rolling is required, the antifriction-roller 12 is mounted on the arm 13 of the bell-crank lever 14. This lever is normally vibrated with the arms 2, so as to prevent the tappet-arm 10 engaging the roller 12 by means of its arm 15, coupled to the arm 16 on the shaft 3 by the compressible spring-coupling 17. A rod 19, connected to the top of the arm 13, slides to and fro through the guide-stud 20 in the side frame B, and when it is desired to stop the impression the end 21 of the weighted lever 22, pivoted on the stud 23, is brought down so as to engage the shoulder 24 in the rod 19, thereby holding the lever 14 stationary in order that its roller 12 can be engaged by the tappet-arm 10. To depress the end 21 of the lever 22 automatically, I pivot the bell-crank lever 8 on its stud 23, one arm 25 of which carries an antifriction-roller 26, bearing against the star-wheel 27, having depressions 28 in its periphery. The other arm 29 of the lever 8 has a weighted arm 30 pivoted to it, and the boss 31 of this lever projects across the lever 22. The star-wheel is intermittently operated, so that at every alternate movement of the type-bed one of the depressions 28 is presented to the antifriction-roller 26, and this permits the lever 8 to fall down and depress the lever 22. The star-wheel is fixed on the shaft 33, actuated by the ratchet 32 on its other end, operated by the pawl 34, carried by the lever 35, lifted by a rod 36, connected to the platen or other moving part. The projection 37 on the lever 35 engages a stop-piece 38 on the frame B and prevents the lever falling too far. To stop the impression other than for double rolling, the arm 30 is turned over to the position shown by the broken line in Fig. 2, so that it rests upon and depresses the lever 22. The spring 62 is employed to draw the tappet 10 back against the stop 63 when it is disengaged by roller 12.

In Figs. 5 and 6 the grippers consist of a thin plate 40, having a pivot 41 at each end, fitting in bearings 42, projecting from the platen C. An arm 43 on one of the pivots carries a stud 44, which engages the forked end 45 of the lever 46, pivoted on the side of

the platen and operated by the tappet F. The plate 40 is sufficiently away from the face of the platen to allow the delivery-grippers K and K⁸ to pass into the notches C⁸ in 5 the platen and the plate to lay hold of the sheet.

The feed-table A is carried on the arms A³, projecting from the rocking shaft A⁴, and a rising-and-falling movement is imparted to it. 10 To stop the movement at every alternate stroke during double rolling, the star-wheel 39 is provided on the shaft 33, and a stud 60 is provided on the arm A³, and at every alternate stroke one of the projections 9 on the 15 star-wheel engages the stud 40 and keeps the table from falling. When double rolling is not required, the pawl 34 is disengaged from its ratchet.

The tappet F is pivoted on the side of and 20 moves with the platen, and it is provided with an arm F², which plays between and alternately engages two projections F³ and F⁴ upon the lever F⁵, mounted upon the rocking shaft C². While the platen travels from beneath the feed-table into position to receive 25 the impression the gripper 40 remains closed and retains the paper; but after the impression is made and the type-bed D has sufficiently receded the antifriction-roller F⁶ upon 30 the lever F⁵ passes off the proud part F⁷ of the cam F⁸, and the lever, moving under the influence of its spring F⁹, brings its projection F³ against the tappet-arm F² and moves the tappet sufficiently to open the grippers. 35 As the platen moves back to beneath the feed-table the tappet is held in position to hold the gripper 40 open by the spring-detent G, pivoted to the side of the platen, engaging the rounded notch G² in the tappet; but when 40 the proud part F⁷ engages the antifriction-roller F⁶ the projection F⁴ moves the tappet so as to disengage it from the roller E¹⁷ and allow the gripper to close upon the edge of 45 the paper projecting over the feed-table.

45 Instead of moving the platen it may normally lie in the position shown in Figs. 7 and 8. In this case a gripper-bar 50 is employed, fixed to the arms 51 and 52, rigidly secured to the rocking shaft C². The edge of the 50 sheet is engaged between the grippers E and the bar 50. The grippers E^x are fixed on the gripper-shaft E³, mounted in bearings 54 in the arms 51 and 52, and the grippers are opened by the pinion 55 on the end of the 55 shaft E³ engaging the toothed sector 56 on the end of the lever 57, operated in the same way as the lever 45. In this arrangement the grippers turn completely over to the position

shown in Fig. 8 and form no obstruction to the delivery of the sheet. 60

I claim—

1. In combination with the platen and the pivoted arms carrying the type-bed, of rods D² for rocking said arms, eccentric connections between said rods and arms, a tappet 65 for shifting said eccentric connection, a yielding stop against which said tappet contacts and means for holding said yielding stop stationary, substantially as described.

2. In combination with the platen and the pivoted arms carrying the type-bed, of rods 70 for rocking said arms, eccentric connections between said rods and arms, a tappet for shifting said connections, a spring-pressed lever carrying a roller for contact with said tappet and means for automatically holding said lever against yielding, substantially as described. 75

3. In combination with the platen and pivoted arms carrying the type-bed, of rods for 80 rocking said arms, an eccentric connection between said rods and arms, a tappet for shifting said connection, a yielding stop or abutment for coacting with said tappet, a weighted lever, a lever 8 coöperating therewith, an intermittently-operated star-wheel and connections whereby the release of the weighted lever by the star-wheel and lever 8 holds yielding stop stationary, substantially as described. 85

4. In combination, the platen and pivoted type-bed-carrying arms, the operating-rods eccentrically connected to said arms, the tappet for shifting said eccentric connections, a yielding lever 14, a stop 12 carried thereby 95 for contact with the tappet, a rod 19, a weighted lever 22, a lever 23, a star-wheel co-operating therewith and a hand-lever 30 mounted on said lever 8 and coacting with said weighted lever, substantially as described. 100

5. In a printing-press, the combination with the rising-and-falling feed-table, of means for preventing the falling of the table independent of its normal operating means comprising a star-wheel, a projection from the table resting upon said star-wheel, and means for rotating said star-wheel, substantially as described. 105

In witness whereof I have hereunto set my hand in presence of two witnesses.

FRED WAITE.
